UNITED STATES PATENT OFFICE.

WILLIAM JENKINS, OF MEAFORD, ONTARIO, CANADA.

PLANER-GUARD.

1,094,657.

Specification of Letters Patent. Patented Apr. 28, 1914.

Application filed March 7, 1913. Serial No. 752,718.

To all whom it may concern:

Be it known that I, WILLIAM JENKINS, of the town of Meaford, in the county of Grey, in the Province of Ontario, Canada, have invented certain new and useful Improvements in Planer-Guards, of which the following is the specification.

My invention relates to improvements in planer guards, and the object of the invention is to devise a form of guard which will effectually protect the hands of the operator of the planing machine when passing the board over the planer table past the knives and which may be adjusted to any width of board, and it consists essentially of a plate, a telescopic frame supporting the plate, compression springs designed to hold the frame normally in its extended position, guide arms extending from each side of the plate and in proximity to each end thereof in an angular direction, a vertically journaled friction roller carried by the frame and designed to bear against the gage block or fence of the planer table, horizontal rollers carried by the end of the frame in proximity to the gage block or fence a supporting arm pivotally connected to the planer table, a bracket depending from the outer end of the frame and to which the supporting arm is pivotally connected at one side of the center of the bracket, an arm pivoted to one side of the table carrying a block an arcshaped rod extending freely through the block and pivotally connected to the end of the supporting arm, a tension spring connected at one end to the rod in proximity to the supporting arm and at the other end to the block, and a clamping screw extending through the block against the rod as hereinafter more particularly explained by the following specification.

Figure 1, is a general perspective view of my device as applied to a planer. Fig. 2, is an enlarged plan view of my device. Fig. 3, is a cross sectional view on line $x-y$. Fig. 2. Fig. 4, is an enlarged perspective detail of the main portion of the guard. Fig. 5, is a cross sectional view on line $x'-y'$. Fig. 2. Fig. 6, is a detail of one of the connecting brackets.

In the drawings like letters indicate corresponding parts in each figure.

A is a planer table of any suitable form provided with the usual planer shaft A' on which are mounted the usual planer knives.

B is the gage block or fence of the planer table which is adjusted crosswise of the table in the usual manner, according to the width of board to be used.

C is the main plate of the planer guard provided with flanged sides C' and an open top C² across which extends the bars C³ forming a grid.

D is a bracket comprising a downwardly curved tip portion D', a vertical portion D² and an inwardly extending portion D³.

D⁴ are cylindrical plugs connected to the vertical portion of the bracket D by bolt D⁵.

D⁶ is a bracket located at the inner end of the plate C and provided with upwardly and outwardly inclined arms D⁷ and D⁸ forming guiding edges D⁹ against which the board is passed horizontally through the planer and guiding faces D¹⁰ against which the board is passed vertically through the planer. It will be noticed that the arm D⁸ is a long arm and projects from that side of the guard beneath which the board is fed. The arm D⁷ is a comparatively shorter arm and merely acts to prevent any jar on the guard as the board passes beyond the same.

E and E' are telescopic bars. Each of the bars E and E' comprise the tubular members E², E³ and E⁴. The plugs D⁴ are threaded in to the outer end of the tubular member E², and connected as before described by the bolts D⁵ to the bracket D.

E⁵ are annular collars secured within the opposite end of the tubular member E². The members E³ are provided with outer collars E⁶ which engage with the collars E⁵ when the telescopic members are drawn out to their fullest extent. The members E³ and E⁴ are connected together similarly to the members E² and E⁵. The bracket D⁶ is provided with a horizontal flange D¹¹.

D¹² is a bolt extending through the inner end of the tubular member E⁴ and connecting plate E⁸, the horizontal flange D¹¹, and plate C together, being secured therein by the nuts D¹³.

F is a compression spring located within

the tubular members E², E³ and E⁴ between the vertical portions of the bracket D⁶ and the plugs D⁴.

G is supplemental supporting plate connected to the inwardly extending flange D³ of the bracket D.

H is a bridge frame extending under and over the frame formed by the tubular members E and E', and provided with lugs H' extending to each side of the tubular members E and E'. The bridge frame H extends upwardly at an angle at each side of the planer guard and has a plate H² connected thereto designed to bear upon the upper surface of the board.

G' is a bolt extending through the lower portion of the bridge frame, the plate G and the plate H² connecting them together.

I, I' and I² are cross plates provided with lugs I³. The lugs I³ of the plates I' and I² extend to the inside of the side flange I⁴ of the next adjusting plate and are pivotally connected thereto by the screw bolts I⁶.

I⁷ is an upturned lip extending from the plate I² and forming a handle.

I⁸ is an upturned plate forming a handle secured to the inner end of the plate C.

J is a lug extending outwardly from the horizontal portion D¹¹ of the bracket D⁶.

J' is an arm pivoted on the bolt J² extending through the lug J.

J³ is a projection extending downwardly from the portion D¹¹ against one side of the arm J. J⁵ is a tension spring connected to the same side of the arm J' and to the portion D¹¹ of the bracket D⁶ at a suitable point.

J⁶ is a roller journaled in the forks J⁷ of the arm J on the pin J⁸.

J⁹ and J¹⁰ are rollers journaled in the arms D⁷ and D⁸ on the pins J¹¹.

K is a plate having a down turned outer end K' and a headed inner end K².

K³ is a plate secured to the upper surface of the bridge bar H and forming a slit through which the plate K slidably extends.

K⁴ is a hook swung in the beaded end of the plate K and designed to engage in one of the cross bars C³ of the grid extending across the open face of the main plate C.

L is a supporting arm pivoted at one end to the side of the planer table and intermediate of its length by the bolt L' to the vertical portion D² of the bracket D on that side of the center from which the board is delivered from the planer or in other words on that side of the planer from which the arm D⁷ extends from the planer guard. In this way it will be readily understood that the receiving end of the guard or that side beneath which the hand of the workman is liable to pass is held normally by its own weight against the surface of the planer table thereby preventing any liability of the

workman's hand getting in contact with the 65 knives when placing the board in position to enter beneath the guard.

L² is a rod pivotally connected at its upper end to the free end of the arm L.

M is a right angular bracket extending 70 over the outer edge of the planer table in proximity to the outer end of the arm L. The inner edge of the upper arm of the bracket M is beveled inwardly toward the board and toward that side away from the 75 planer guard.

M' is a projection extending downwardly from the bracket M into a recess M² in the planer table. A set screw M³ extends through the bracket M against the side of 80 the planes forming with the projection M' in the recess M² a support for the bracket.

Pivotaly connected to the bracket M and depending therefrom is a plate M⁴ provided at its lower end with a block M⁵. This 85 block is provided with a vertical aperture through which the rod L² freely extends.

A tension spring M⁶ surrounding the rod L² is secured at its lower end to the block M⁵ and at its upper to a pin M⁷ extending 90 through an opening in the rod L².

A series of openings M¹¹ is provided and by moving the pin M⁷ from one to another the tension of the spring M⁶ may be varied. In some cases the operator may desire to run 95 a board through the machine without any pressure thereon. In order to do this the planer guard carried by the arm L is forced upwardly and the set screw M⁸ locked against the rod L² so as to hold the planer 100 guard in a position above and free of the board.

Having now described the principal parts involved in my invention, I will briefly describe the operation of the same.

The board to be planed is placed on the table in the usual manner against the gage block B and passed beneath the upwardly inclined ends of the arms D⁸ and H². The board is then forced longitudinally beneath 110 such arms turning the planer guard upwardly on its pivot formed by the bolt L'. The spring acting to counter balance the weight of the guard. The board is then passed through the planer in the usual manner and as it passes from the planer knives the butt end of the board engages the inclined guarding surface of the arm H² and D⁹ of the arm D⁷ allowing the planer guard to gradually drop to its normal position 120 without jar. It will also be understood that as the board is passed beneath the planer guard the roller J⁶ contacts with the gage block B rolling vertically up the same.

When a narrower board is to be planed 125 and it is desired to adjust the gage block B toward the outer end of the table this is done in the usual manner, the hook K⁴ be-

ing first removed from engagement with the cross bars C³. The operator then grips the handle I⁸ drawing the main plate C longitudinally telescoping the tubular members E², E³ and E⁴ against the compression of the springs F. The hook K⁴ may then be swung downwardly to engage another of the cross bars C³.

If it is desired to trim the edge of the board, the board is passed over the planer in the position shown by dotted lines in Fig. 2, of the drawing and against the rollers J¹¹ collapsing the planer guard more or less toward the position shown in dotted lines, according to the thickness of the board passed over the planer. When it is desired to give a slight bevel to the surface of the board, the gage block B is adjusted so as to hold the outer edge of the board on the beveled arm of the bracket M thereby canting the board slightly upwardly as it passes over the planer.

If for any purpose it is desired to remove the guard, all it is necessary to do is to loosen the set screw M⁸ and remove the bracket M. The arm L may then be swung on its pivot carrying the guard free of the table. It will also be noticed that in my construction of guard the open top of the guard plate C provides for the operator observing how much and when to adjust the cutting knives of the planer.

From this description it will be seen that I have devised a very simple form of planer guard which will insure of the hands of the operator being protected, no matter what size board is being passed over the planer, and such a device as may be adjusted to various sizes and thicknesses of boards. It will also be seen that my guard will automatically adjust itself to various thicknesses of boards. Also should a board be too thick to enter between the fence and the outer end of the arm D⁸, the frame may be locked back by the hook K⁴.

What I claim as my invention is—

1. A planer guard comprising an arm pivoted at one end to the planer table so as to swing in a vertical plane, a tension device connecting the opposite end of the arm to the table resiliently, an expandable and contractible frame carried at one end by the arm intermediately of its length and bearing at its opposite end against the gage block of the planer table, a gage plate secured at its inner end to the expandable frame, and means for locking the gage plate in the position to which it is adjusted, as and for the purpose specified.

2. A planer guard comprising an arm pivoted at one end to the planer table so as to swing in a vertical plane, a resilient device connecting the opposite end of the arm to the table, an expandable and contractible

frame carried at one end by the arm intermediately of its length and bearing at its opposite end against the gage block of the planer table, a plate secured at its inner end to the expandable frame having an open top having a series of cross bars extending across the opening to form a grid, and a hook carried by a stationary portion of the frame and designed to engage with the cross bars and hold the frame in the position to which it is adjusted and means for guiding the board beneath the frame, as and for the purpose specified.

3. A planer guard comprising an arm pivoted at one end to the planer table so as to swing in a vertical plane, a resilient device connecting the opposite end of the arm to the table, an expandable and contractible frame carried at one end by the arm intermediately at its length and bearing at its opposite end against the gage of the planer table, a plate secured at its inner end to the expandable frame having an open top having a series of cross bars extending across the opening to form a grid, means for guiding the board beneath the frame, a plate located over the guard plate and slidably longitudinally in the stationary portion of the frame, a stop at one end of the plate and a hook swingably connected at the opposite end of the plate and designed to engage with the bars of the grid opening, as and for the purpose specified.

4. A planer guard comprising a supporting arm pivoted at one end to the planer table to move in a vertical plane, resilient connecting means between the opposite end of the arm and the planer table, a frame carried by the supporting arm intermediately of its length and a guard plate carried thereby, means for guiding the board beneath the frame, an arm pivoted to the inner end of the frame vertically set roller journaled in the arm and bearing against the gage block of the planer table, a stop depending from the frame to one side of the roller, and a tension spring normally holding the arm against such stop, and horizontal rollers journaled to each side of the first mentioned horizontal roller and designed to bear against the surface of the board when passed edgewise over the planer knives, as and for the purpose specified.

5. A planer guard comprising an arm pivoted at one end to the planer table so as to swing in a vertical plane, resilient means for connecting the opposite ends of the arm to the planer table, an expandable and contractible frame carried by the arm having a downward curved lip at its end, a main guard plate secured to the inner end of the frame, supplemental guard plates pivotally connected together in series and said series being connected to the main guard plate

and designed to be supported by the curved lip when the frame is adjusted into its contracted position and means for guiding the board beneath the guard, as and for the 5 purpose specified.

6. A planer guard comprising an arm pivoted at one end to the planer table so as to swing in a vertical plane, resilient means for connecting the opposite end of the arm 10 to the table, an expandible and contractible

frame supported by the arm, guide arms inclined inwardly from the inner end of the table and adjustable means for resiliently holding the frame partially contracted, as and for the purpose specified. 15
